UNITED STATES PATENT OFFICE

HARRY M. CREIGHTON, OF EAST NORWALK, CONNECTICUT, ASSIGNOR TO R. U. V. COMPANY, OF NEW YORK, N. Y., A CORPORATION OF NEW YORK

INLET FITTING

Application filed August 30, 1928. Serial No. 303,009.

This invention relates to inlet fittings for fluid tanks, reservoirs, swimming pools and similar fluid containers.

A primary object of the invention is to provide an inlet fitting of the nozzle type in which a member is permanently fixed within the wall of the reservoir or pool and the position of the nozzle is adjustable with respect to the fixed member.

10 Another object of the invention is to provide a nozzle fitting in which the nozzle may be removed, without mutilating the permanent fluid container wall with the possibility of injuring the water-proofing of the wall 15 which renders it impervious to fluids, and replaced by another nozzle of different form or shape.

These and other objects of the invention and the means for their attainment will be 20 more apparent from the following detailed description taken in connection with the accompanying drawing illustrating a preferred embodiment thereof, in which

Fig. 1 is a sectional view through a preferred form of the inlet fitting as it is positioned within the wall of the pool or tank.

Fig. 2 is an end view of the inlet fitting set in the wall as it appears from the inside of the tank or pool.

30 Fig. 3 is a sectional view of a modified form of the invention also set in the wall of the pool or tank.

In nozzle type inlet fittings for tanks, pools and such fluid containers it has been 35 the practice to make the nozzle of a single member and embed it in the wall of the tank or pool and it then becomes a permanent part of the wall and remains fixed therein. Usually the nozzle was permitted to project beyond the face of the foundation wall a predetermined distance so that a desired thickness of filling or grouting could be added to the 40 face of the wall and the grouting faced with a finishing tile or brick. Due to inaccuracies in the building of the pool or tank wall or inaccuracies in the positioning of the nozzle or if the wall is of concrete, which is the usual material used for building tanks and 45 pools, the concrete forms would warp or be 50 inaccurately placed so that when the wall was

completed, it was found usually that the nozzle projected too far beyond the wall face or not far enough so that the nozzle must necessarily be cut off in the former case and in the latter case an extension must be laboriously added or the grouting or tile or both must be smoothed about the nozzle opening and in that way form an aperture to the nozzle end in the wall. My invention contemplates overcoming these difficulties by making the 55 inlet fitting of two parts, one part being permanently fixed within the wall and the nozzle part being a separate member and adjustable with respect to the fixed member and the wall face.

The invention shown in its preferred form in Fig. 1 consists of the sleeve 1 embedded within the wall 2 and may be of bronze or any other material but is preferably made of some rust resisting metal. The sleeve is internally threaded at both ends 3 and 4 forming an elongated chamber 5 between the threaded ends. The threaded end 3 receives the end of the pipe P which leads to the fluid supply mains.

Fig. 2 is an end view of the inlet fitting set in the wall as it appears from the inside of the tank or pool.

75 A flange 11 may be provided upon the sleeve 1 which is embedded within the wall 2 so that its outer face is flush with the surface of the wall. The purpose of the flange is to assure a water-proof joint or bond between the wall and sleeve. This is secured by applying a water-proofing layer 12 over the surface of the wall 2 which overlaps the face of the flange 11. Since the water-proofing layer overlaps a large portion of the face of the flange, a water-tight bond between the layer and the flange is secured. It is to be understood that this flange is not a necessary element of my invention and that my adjustable inlet fitting will function equally well if the sleeve 1 is merely a straight sleeve member without the flange.

80 Although I have shown the sleeve 1 as extending but part way through the total wall thickness, it may nevertheless extend all the 85 way through the wall and the reason for constructing it as shown, is to reduce the amount used of the more expensive bronze material of which this sleeve is preferably made. The sleeve however must be long enough to enable 90 95 100

a sufficient adjustment of the nozzle to be made therein. The amount of adjustment depends upon the inaccuracy with which the sleeve is embedded within the wall and may be considerable in some instances and nil in 5 other instances.

A nozzle 6 which may have any desired degree of taper is externally screw threaded at 7 which threads engage the threaded end 10 4 of the sleeve. This nozzle 6 is screwed into the sleeve 1 so that the large end enters the center chamber 5 of the sleeve and the smaller end projects beyond the sleeve end. The threaded portion 4 of the sleeve is long 15 enough so that the threads 7 of the nozzle 6 will continue to engage the threads 4 of the sleeve for a considerable axial adjustment of the nozzle within the sleeve. The chamber 5 is also of sufficient length so that the large 20 end of the nozzle may freely move therein for the full adjustment distance.

After the sleeve 1 is fixed in position in the wall 2 and the nozzle adjusted so that it projects the desired distance from the wall 25 face or the sleeve end, a water-proofing material 12 of any known type is applied to the face of the wall and covered with a filling or grouting 13 which is then faced with a tile or brick 14, the outer surface of which is 30 flush with the end of the nozzle. By making my nozzle adjustable with respect to the face of the wall 2 I am able to apply any desired thickness of grouting and still have the end 35 of the nozzle flush with the finished tiled or bricked face.

A plate 8 is lastly fastened to the end of the nozzle by means of a pair of screws 9 which gives the nozzle a finished appearance at the tiled or bricked wall surface 13. It 40 is clear however that this plate is not a necessary feature of the invention and may be dispensed with. Its function is to cover the cracks and rough edges necessarily existing where the tile 14 is broken away to fit the 45 tile around the end of the nozzle. The sole purpose of the plate is to improve the appearance of the inlet opening.

The nozzle 6 may have a groove 15 into which the filling material 13 is tamped so 50 that the nozzle is rigidly secured in final adjusted position. This groove, however, is not a necessary part of the nozzle and may be dispensed with if so desired and the nozzle diameter may be made uniform throughout 55 its length excepting for the threaded portion 7 which must exceed the diameter of the nozzle body in order to secure the adjustment of the nozzle in the sleeve.

In the modified form of my invention as 60 shown in Fig. 3 I extend the fluid supply pipe P into the wall 2 and screw thread a coupling 17 on the end of the pipe. This coupling may be taper threaded at one end 65 18 to receive the end of the threaded pipe P. The other end 19 of the coupling projects

beyond the end of the pipe P and is screw threaded with a straight thread so that it may receive the threads 20 of the nozzle 21 and so that its adjustment axially with respect to the pipe and the coupling may be 70 secured by screwing the nozzle into the coupling. The nozzle in this modified form projects beyond the face of the wall 2 in the same manner that the nozzle projects from the sleeve in Fig. 1 and the nozzle is also 75 adjustable with respect to the face of the wall 2. The grouting and tile is then applied to the wall 2 in the same manner that the grouting and tile is applied in the sleeve and nozzle construction shown in Fig. 1. 80

After the nozzle has been fixed in position and the filling or grouting and tile cemented on the face of wall 2, it may be found that the nozzle is not of the proper proportions and it may be desirable to change it. 85 With my invention this is a very simple operation since it merely involves removing the plate 8, if such a plate has been provided, and chipping narrow apertures into the tile and filling or grouting about the nozzle so 90 as to clear a passage for the nozzle. The nozzle is then unscrewed from the sleeve and replaced by a nozzle of the proper proportions after which the spaces or openings about the nozzle are again filled in with cement or filling and the plate screwed on the end of the newly inserted nozzle. With my 95 inlet fitting, the nozzle may be replaced without injuring or cutting into the water-proofing layer or if a water-proof mixture of concrete has been used the concrete wall need 100 not be cut into in order to replace or remove the nozzle.

It may be desirable in certain constructions of tanks and pools to have a nozzle 105 which is replaceable at will in which case a permanent aperture 22 may be made through the tile and grouting or filling large enough to allow the nozzle to pass freely through the aperture. The end plate 8 is large enough 110 to cover this aperture and present a smooth continuous wall just as if the opening were not present and the nozzle were fixed in the sleeve and wall as described above.

What I claim:

1. An inlet fitting for fluid containers having walls lined with a facing at a fluid inlet comprising a fixed fluid conducting member adapted to be embedded in the wall of the container and connected to a source of fluid supply and a tapered nozzle projecting beyond the fixed member and carried by and adjustable with respect to the member to adjust its end in predetermined relation with the wall facing. 120

2. An inlet fitting for fluid containers having walls lined with a facing at a fluid inlet comprising a sleeve adapted to be embedded in the wall of the container and connected to a source of fluid supply and a tapered noz- 130

zle having its smaller end projecting beyond the end of the sleeve and carried by and adjustable with respect to the sleeve to adjust its end in predetermined relation with the 5 wall facing.

3. An inlet fitting for fluid containers having walls lined with a facing at a fluid inlet comprising a sleeve adapted to be embedded in the wall of the container and connected 10 to a source of fluid supply, and a tapered nozzle within the sleeve and having its smaller end projecting beyond the sleeve end, said nozzle being carried by and adjustable axially with respect to the sleeve to adjust its 15 smaller end in predetermined relation with the wall facing.

4. An inlet fitting for fluid containers having walls lined with a facing at a fluid inlet comprising a sleeve adapted to be embedded 20 in the wall of the container and connected to a source of fluid supply, screw threads within said sleeve and a tapered nozzle externally threaded and engaging the threads within the sleeve, the smaller end of said nozzle 25 projecting beyond the sleeve end and being adjustable axially with respect to the sleeve end by means of the screw threads to adjust its end in predetermined relation with the wall facing.

30 5. An inlet fitting for fluid containers having walls lined with a facing at a fluid inlet comprising a sleeve adapted to be embedded in the wall of the container and connected to a source of fluid supply, a tapered nozzle 35 having its smaller end projecting beyond the end of the sleeve and carried by and adjustable with respect to the sleeve, to adjust its end in predetermined relation with the wall facing and a plate upon the end of the nozzle.

40 6. An inlet fitting for fluid containers having walls lined with a facing at a fluid inlet comprising a fixed fluid connecting member adapted to be embedded in the wall of the container and connected to a source of fluid 45 supply, a flange projecting from said member and a tapered nozzle having its small end projecting beyond the fixed member and carried by and adjustable with respect to the member to adjust its end in predetermined 50 relation with the wall facing.

7. An inlet fitting for fluid containers having walls lined with a facing at a fluid inlet comprising a fixed fluid conducting member adapted to be embedded in the wall of the 55 container and connected to a source of fluid supply and a tapered nozzle removably secured to said fixed member to permit nozzle substitution.

8. A container wall comprising a foundation wall, a fixed member embedded in the foundation wall and connected to a source of fluid supply, a taper nozzle having its smaller diameter projecting beyond the fixed member and carried by and adjustable with respect to the member to adjust its end in pre- 60

determined relation with the face of the foundation wall, and a lining of predetermined thickness upon the face of the foundation wall and surrounding the nozzle end so that the end of the taper nozzle is flush with the 70 outer face of the lining.

In testimony whereof I affix my signature.
HARRY M. CREIGHTON.
